United States Patent Office

Des. 196,525
Patented Oct. 8, 1963

196,525

CLOCK OR SIMILAR ARTICLE

Carl N. Johnson, Stratford, and William V. Judson, Westport, Conn., assignors to General Electric Company, a corporation of New York

Filed Apr. 25, 1962, Ser. No. 69,845

Term of patent 14 years

(Cl. D42—7)

Fig. 1.

Fig. 2.

Fig. 3.

Fig. 4.

Fig. 5.

Fig. 6.

FIG. 1 is a front perspective view of a clock embodying our new design;

FIG. 2 is a top plan view of the clock shown in FIG. 1;

FIG. 3 is a front elevational view of the clock shown in FIG. 1;

FIG. 4 is a side elevational view of the clock shown in FIG. 1;

FIG. 5 is a rear elevational view of the clock shown in FIG. 1; and

FIG. 6 is a bottom plan view of the clock shown in FIG. 1.

The characteristic features of our design include the dial face which has a clear area encompassing the numerals and sub-hour indicators surrounded by a shaded area; the V-shaped alarm button which complements the

inverted V-shaped supporting base, and the outwardly projecting crystal.

We claim:

The ornamental design for a clock or similar article, substantially as shown.
